TAKE-OUT FOR GLASSWARE MAKING MACHINES

Edward Miller, Columbus, Ohio, assignor to Lynch Corporation, Anderson, Ind., a corporation of Indiana

Application June 17, 1933, Serial No. 676,301

17 Claims. (Cl. 49—14)

This invention relates to glassware forming machines such as glass blowing or pressing machines and more especially to bottle manufacturing machines in which a series of glass forming molds is moved in a circular path, each piece of finished ware being removed when it arrives at a station to a belt which carries them away.

The principal object of the invention is to provide improved mechanism whereby the bottles or other similar ware are automatically and rapidly removed upon completion of the pressing and blowing operation without serious loss by breakage of the ware or injury to the machine or parts thereof. Other objects will appear from the disclosure herein.

The invention is embodied in the example herein shown and described, the features of novelty being finally claimed.

In the accompanying drawings—

20 Figure 1 is a plan view with parts broken out and in section of a sufficient fraction of glass pressing or blowing machine showing my present invention embodied therein.

25 Fig. 2 is mainly a sectional view on the line II—II Fig. 1 with parts in full illustrating a portion of the power transmitting means.

Fig. 3 is a vertical sectional view illustrating the bottle centering and gripping devices and the mechanism for operating those devices.

30 Figs. 4 and 5 are elevations of the grooved faces of the left and right cams shown in the upper portion Fig. 3.

Fig. 6 is a general view partly in full and partly in section looking toward the right hand side of Fig. 1, the sectional portion at the top of this view being taken on the line VI—VI, Fig. 1.

Fig. 7 is a detail plan view, on a larger scale, of the take-out swinging and rotating mechanism, parts being broken out and omitted.

40 Fig. 8 is a view looking at the lower end of the take-out rotating table as seen at the right hand end of Fig. 7.

Fig. 9 is a perspective of a dog employed.

In the views A designates a base, B a center column around which the molds C travel as customary in some of such machines in common use. D designates the main drive worm, E a worm gear engaged by the main drive. In the illustrated embodiment the mold carrier is moved intermittently and the gear E revolves an eccentrically located rotary block F for engaging the slots of a wheel G thereby intermittently rotating a table or carrier on which the molds are carried. The devices F and G constitute a Geneva movement of the species illustrated in an application

for patent of the United States filed by me April 16, 1932, S. No. 605,680.

The ware gripping and lifting mechanism and the ware take-out mechanism of my invention are supported in a suitable frame, carried by the frame A of the machine.

Bottle gripping and lifting mechanism

This mechanism includes a plurality of jaws 10 (see Fig. 3) adapted to grip the bottle at the exterior of its lip 11, the stem of said jaws being slidable in hollow arms of bell crank levers 12 fulcrumed to ears on said lower end of a sliding tubular member 19. The other arms of the bell crank levers 12 are pivotally connected by means of a pin and tube member 14 to ears on the upper end or head member of a sliding sleeve 13.

The jaws 10 are each yieldably mounted in the hollow arm of its bell crank lever 12 as by means of a spring 15, so that each jaw 10 may yield in case it should strike the top of a mold and the downward movement of the jaws are each limited by a small bolt 16 extended through a slot 17 in the hollow arm of the bell crank lever. A coiled spring 18 is interposed between the pin and tube 14 of the member 14 to give cushion and safety action.

The tubular member 19 is inserted in the axis of the sleeve member 13 and said tube 19 has at its lower end an annular shoulder between which and an opposed shoulder in the upper end of the sleeve member 13 is a coiled spring 20 tending to open the jaws.

In the axis of the tubular member 19 is a plunger rod 21 carrying a beveled pilot member 22 or 35 centering device to engage the mouth of the bottle to keep the bottle from moving to one side when mold is opened and from falling off of the mold bottom. Said pilot member has a stem that extends into a tubular portion of the lower end of the rod 21, and is provided with a groove that is entered by a small bolt 23 permitting a limited vertical and yielding movement of the pilot to prevent injury thereto in the event the mold is not properly opened. Said pilot is pressed down by a coiled spring 24 inserted between the upper end of the stem of the pilot and a cross pin in the tubular portion above so that when the plunger rod is forced down a yielding pressure is exerted on the inner side of the lip of the bottle by the pilot when the latter is entered thereagainst if off center.

In practice the jaws are normally pressed asunder while the pilot is elevated slightly above the plane of the lip of the bottle; and to engage the bottle when it arrives under the apparatus

just described the pilot is first caused to descend slightly into the bottle and then the jaws clamped against the under side of the lip. When the shovel is under the bottle the jaws leave first and the pilot last but before the outward stroke of the shovel.

The principal function of the pilot is to keep the bottle from shifting on the mold bottom and hold it in proper position to be engaged by the gripping jaws. An important function of the gripping jaws is to insure the lifting of the bottle sufficiently from its support to permit the insertion thereunder of the take-out devices to be herein-after described.

15 The depression of the pilot is effected by means of a suitable cam 25 on a horizontal shaft 26 driven by suitable gearing with a vertical shaft 27, the latter extending in a fixed hollow housing or column 28, said vertical shaft 27 receiving power 20 from a take-off of the main drive D through a shaft 29^a and worm gear 29 keyed on the lower end of shaft 27 (see Fig. 2). The cam 25 is provided with a groove 25^a that is engaged by a roller 30 on a short shaft 31 connected with the plunger 25 rod 21, said shaft extending through a longitudinal slot 32 in the tubular member 19 so that the pilot can be operated by its actuating cam 25 independently of the operation of the gripping jaw tubular member 19.

30 The gripping jaws are actuated by a cam member 33 secured on said horizontal shaft 26, said cam member 33 being provided at its rim with an excrescent portion at 33^a that acts in an anti-friction roller 34 journaled in the head of the sleeve member 13. The action of said excrescent portion 33^a is to throw the gripping jaws inward toward each other after the pilot 22 has centered the bottle. The cam member 33 is provided at its face with a groove 33^b engaged by a roller 35 to 40 lift first the sleeve member 13 and the gripping jaws independently of the pilot 22 when the bottle is to be released for transference by the take-out devices.

Bottle take out

45 The bottle take out mechanism as shown includes a four armed frame provided at the end of each of its arms with a shovel-like blade, said four armed frame being journaled to be intermittently rotated and swung to project the shovel-like blades in succession under the elevated bottles to receive, support and transfer them to a belt for carrying them away, as to a lehr.

50 Referring more particularly to Figs. 1, 2, 6, 7, 8, and 9 the character 40 designates the shovel-like blade of the four armed frame, said frame having a central shaft 41 journaled in a block 42 sliding in a groove 43 formed on or in a piece secured to a bed or plate 44 secured to the upper end of a 55 stationary post 45. The shaft 41 is engaged by the free end of a horizontal arm 46 pivoted at 47 and said arm is swung outward by a cam 48 on the vertically driven shaft 27 before referred to and said arm is swung inward by a spring 49 connecting the arm and shaft housing.

55 The shaft 41 carrying the shovel-like blades has secured to rotate with it a disk 50, said disk having four equally spaced downwardly projecting studs 51 with rollers on them, and pivoted at 60 52 on the bed or plate 44 is an L-shaped dog 53 having an inclined end 53^a at its lower leg, and a cutaway portion 53^b at the juncture of the legs. The outer portion of the dog is made heavier than the inner portion so that in normal position the dog lies horizontally as shown by full

lines Fig. 8, the inner end being intermittently depressed by the passage of the pins 51 over it when the arm 46 is swung inward. The stop 55 limits the position of the dog to horizontal position when the pressure of a pin 51 is removed. The inward stroke of said arm 46, due to the draft of the spring 49, carries one of the shovels 40 to position under the elevated bottle to receive that article when released by the grippers. The outward stroke of said arm 46 causes a quarter 10 rotation of the shovel wheel because on that stroke the pin 51 that has been carried over the top of the dog on the next preceding inward stroke is now arrested in the cut-away portion of the dog while the block 42 is carried to the 15 terminus of the outward stroke. In this operation it will be observed that the cut away portion of the dog forms a fulcrum for the arrested pin and permits the rotation of the rest of the wheel and its pins 51 by block 42 and arm 46 thereby causing in the mechanism, as embodied, a quarter rotation of the pin, disk and shovel wheel. In this operation the pin that is next to operate the dog is advanced in front of the inclined end of the inner leg of the dog as shown 25 in Fig. 7. To overcome any lag in the final movement of the wheel to the position described and shown there is provided a kicker 56 pivoted at 57 and pressed by an adjustable coil spring 58, against the inclined wall 56^a on which the approaching pin slides thereby compressing the spring 58 and causing the kicker to impart an impulse to the wheel supplementing the lever action of the arm 46 to establish a quarter turn on the disk and placing the next advanced pin 35 51 in position to go over the top of the incline of the dog leg and into the recess of the dog beyond; or briefly again to the position shown in Fig. 8. In some instances the kicker may be dispensed with.

40 60 designates a belt for conveying the bottles away as to a lehr. 61 designates a stationary curved rail carried by the arm 46 to confine the bottles to the shovels in transit from the point of take-out to the belt 60. The character 62 designates a stationary finger connected with the stationary plate 44, said finger bent upwardly into position to contact with the side of the bottle to hold the bottle for deposit on the carrier belt 60 while the shovel draws away from it as the 50 shovel-carrying frame is swung toward a mold to take another bottle.

Guard members 41^a on the shaft 41 can be provided to assist in retaining the bottles on the shovels between the bottle taking operations of 55 the shovel frame.

The travel of the molds, the oscillation of the arm 46 and the operation of the bottle lifting device are synchronized or timed to cause and permit the shovels in succession to take a bottle 60 in an interval between the movements of the molds.

From the above it will be apparent that as the mold with the ware in it, arrives at the take-out station, the mold is opened and the ware is 65 steadied by means of the plug 22 operated synchronously with the machine. Immediately the ware is elevated by the grippers 10 and simultaneously therewith the frame 46 is moved toward the ware, positioning one of the supporting 70 members 40 under the ware so that it may be supported solely thereby. As the frame 46 moves away from the mold, the carrier for the supports 40 is indexed, so that an empty support is available for the next bottle. Hence, the take-out is 75

much faster than such mechanism heretofore used, which necessitates either a plurality of grippers or requires complete travel from the mold to the conveyor for each operation.

5 The forms, proportions and numbers of the parts can be changed without departing from the gist of the invention as claimed.

What I claim is:

1. In a glassware making machine having a mold provided with a bottom, means for centering the ware on said bottom as the mold opens, means for gripping the ware, means for operating said ware centering and gripping means to elevate the ware from the mold bottom, means for moving a supporting means under the elevated ware, and means for then releasing the gripping means and moving the supporting means laterally away from the mold.

2. In a glass ware making machine having a pressing or blow mold provided with a bottom, a means for centering the ware on said bottom, means for gripping the ware, and means for operating said ware centering and gripping means in succession to center on and elevate the ware from the mold bottom, a shovel-like device to receive and remove the ware from the mold and means whereby said shovel-like device is oscillated toward and from said mold.

3. In a glassware making machine having a shaping mold provided with a bottom, means for moving the mold in a circular path, means stationarily mounted with respect to said movable mold for elevating the ware above the mold bottom, means for removing the ware from said mold bottom, when the mold is opened, including a shovel-like member, means for swinging said shovel-like member toward and under the bottom of the ware to support the same and means for causing said shovel-like member to deposit the ware at a point removed from said mold.

4. In a glass ware making machine having a series of molds provided with bottoms and means for rotating said molds, means for elevating the ware above the mold bottom means for removing the ware from said bottoms when the molds are open including a shovel-like member, means for swinging said shovel-like member toward and under the bottom of the ware to support the ware when a mold arrives at a given station, and means for causing the ware on said shovel-like member to be deposited at a point remote from such mold.

5. In a glass ware making machine having a series of molds provided with bottoms and means for rotating said molds, means for removing the ware from said bottoms when the molds are opened including a rotatable frame carrying a plurality of shovel-like members, means for rotating said frame and means for moving said frame and one of the shovels toward and under the bottom of the ware to receive and support the ware when a mold arrives at a given station, and means for carrying the ware on said shovel to a point remote from such mold.

6. In a glass ware making machine having a series of molds provided with bottoms and means for rotating said molds, means elevating the ware from the bottom of the mold as it arrives at a given station, means for removing ware from said bottom when the mold is open including a plurality of shovel-like members, means for swinging said shovel-like members independently of the elevating means toward and under the bottom of the ware to receive and support the same and means for causing said shovel-like member to

deposit said ware at a point remote from said mold.

7. In a glass ware making machine having a series of molds provided with bottoms and means for rotating said molds, means for removing the ware from said bottoms when the molds are opened including a rotatable frame carrying a plurality of shovel-like members, means for rotating said frame, and means for reciprocating said frame and one of the shovels under the bottom of the ware to receive and support the ware when the mold arrives and is open at a given station, said means for rotating the shovel-carrying frame including a movable dog mounted on a stationary part, said dog constituting a fulcrum cooperating with the frame-reciprocating means to cause partial rotation of said frame.

8. In a glass ware making machine having a movable mold provided with a bottom, a conveyor belt, means for removing ware from said mold bottom, including means stationarily mounted with respect to said movable mold for elevating the ware from said mold bottom, a shovel-like member, means for revolving said member and means for reciprocating said shovel-like member transverse its axis to receive the ware, and means to cause the removal of the ware from the shovel onto the conveyor belt when the shovel is moved toward the mold.

9. In a glass ware making machine having a pressing or blow mold provided with a bottom, a conveyor belt, means to elevate the ware above the mold bottom and means for removing ware from said mold bottom including a shovel-like member, means for revolving said member and means for reciprocating said shovel-like member transverse its axis to receive the ware and stationary means to cause the removal of the ware from the shovel onto the conveyor belt when the shovel is moved toward the mold.

10. In a glass ware making machine having a mold provided with a bottom, a ware take-out mechanism including an oscillating arm, a frame including a plurality of ware-receiving members, said frame rotatably mounted at the free end of said arm, power means for oscillating said arm and stationarily supported means with respect to which said arm oscillates for causing the rotation of said frame.

11. In a glassware forming machine having an openable mold and a mold bottom, means engaging the neck of the ware and operative to elevate the ware from the mold bottom, and means movable independently of said elevating means for supporting the ware from the bottom, and means for moving said last named means and ware supported thereby away from the mold.

12. In a glassware forming machine having an openable mold and a mold bottom, means for moving said mold and mold bottom, means stationarily mounted with reference to said mold and above the mold bottom and operative to elevate the ware from the mold bottom, and means movable independently of said elevating means for supporting the ware from the bottom, and means for moving said last named means and ware supported thereby away from the mold.

13. In a glassware forming machine having an openable mold and a mold bottom, cam operated means for centering the ware on the mold bottom, means engaging the neck of the ware and operative to elevate the ware from the mold bottom, and means movable independently of said elevating means for supporting the ware from the bottom, and means for moving said last

named means and ware supported thereby away from the mold.

14. In a glassware forming machine having an openable mold and a separate mold bottom, means operable synchronously with the opening of the mold for elevating the ware from the mold bottom, and means for moving the ware laterally from its elevated position comprising a multiple-armed support, means for moving one of the supporting arms under the elevated ware and means for releasing the elevating means to permit the ware to be supported wholly by the support.

15. In a glassware forming machine having an openable mold, and a separate mold bottom, means operable synchronously with the opening of the mold for elevating the ware from the mold bottom, and means for moving the ware laterally from its elevated position comprising a multiple-armed support, means for moving one of the supporting arms under the elevated ware and means for releasing the elevating means to permit the ware to be supported wholly by the support, and means for moving the support away from the mold.

16. In a glassware forming machine having an openable mold and a separate mold bottom, means operable synchronously with the opening

of the mold for elevating the ware from the mold bottom, and means for moving the ware laterally from its elevated position comprising a multiple-armed support, means for moving one of the supporting arms under the elevated ware, means for releasing the elevating means to permit the ware to be supported wholly by the support, means for moving the support away from the mold, and indexing said multiple-armed support to bring a fresh supporting member into position to receive the next article.

17. In a glassware forming machine having an openable mold and a separate mold bottom, means operable synchronously with the opening of the mold for elevating the ware from the bottom, means for moving the ware laterally from its elevated position comprising a multiple-armed support, means for moving one of the supporting arms under the elevated ware, means for releasing the elevating means to permit the ware to be supported wholly by the support, and means for simultaneously bodily moving the support away from the mold and indexing it about its own axis whereby the bodily movement of the support is substantially less than the distance between the mold and point of deposit.

EDWARD MILLER.
